UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

ROTARY CYLINDER PRINTING-PRESS.

1,240,008.

Specification of Letters Patent. Patented Sept. 11, 1917.

Application filed September 12, 1912, Serial No. 719,967. Renewed June 30, 1917. Serial No. 177,989.

To all whom it may concern:

Be it known that I, HENRY F. BECHMAN, of Battle Creek, in the county of Calhoun and State of Michigan, have invented certain new and useful Improvements in Rotary Cylinder Printing-Presses; and I hereby declare that the following is a full, clear, and exact description thereof, reference being had to the accompanying drawings, which form part of this specification.

This invention is a novel improvement in rotary cylinder web printing presses and is what I term a "staggered section press" that can print either two narrow webs or one wide web without the employment of long plate cylinders.

The invention in brief comprises a novel arrangement of two sets of printing or, preferably, perfecting mechanisms in one frame, the mechanisms being placed adjacent each other and in different vertical planes and with the cylinders of the printing mechanisms in axial parallelism, the sets of printing mechanisms being so relatively located that the inner side of one printing mechanism slightly overlaps the inner side of the adjacent printing mechanism, and this enables both sets of printing mechanisms to be supplied from one double width roll of paper by simply splitting the web after it leaves the roll, and without any lateral deflection of either half of the split web in order to lead the same to and through its proper printing mechanism.

This invention enables, for example, a four-page web to be printed on either section of the press, and the sections can be supplied with webs either from two separate narrow web rolls, or from one wide web roll; the wide roll is preferable when both sections are operating as it lessens handling of webs. By reason of the peculiar laterally displaced but axially parallel arrangement of perfecting mechanisms when a web is supplied from a wide roll it is simply necessary to slit the web at the proper point and then one-half of it can be led direct to one perfecting mechanism and the other half to the other perfecting mechanism, and after printing, both halves or webs may be directed to separate folders, or if desired may be assembled and directed to the same folder. The printing sections in brief are staggered so that the right hand edge of a web or part of web passing through one

section alines with the left hand edge of the web or part of web passing through the other section. The invention is particularly useful in connection with single page tubular plates such as shown in my Patents 60 No. 867,230 dated October 1, 1907, and No. 979,919 dated December 27, 1910; and it enables me for example to print a four page wide web on short cylinders and yet obtain the effect of four-plate-wide cylinders; and at the same time enables me to slip such plates readily on and off such cylinders from the outside of the press just as in my aforesaid patents; and also to have all the gearing out of the way of the pressman, 70 while yet being readily accessible.

The invention also obviates springing of the cylinders and streaking of the paper when operating at high speed with a narrow web. In the present construction of presses 75 using four-page wide or wider cylinders, it is frequently desired to print a narrow web from plates mounted on only one end or half of the cylinders. This operation produces an uneven strain on such cylinders and results in their "jumping" at high speeds when the margins between the plates reach the impression point; and this "jumping" affects the quality of the printing. In my present invention as only short cylinders 80 are employed a bearing is provided close to each end of the impression surface when a narrow web is run as well as when a wide web is run, and thus each cylinder is firmly supported and springing and jumping prevented, even at the highest speeds.

In the accompanying drawings I have illustrated conventionally one embodiment of the invention in a rotary cylinder press and will explain it more fully with reference thereto.

In said drawings—

Figure 1 is a conventional top plan view of a press showing the general arrangement of the perfecting mechanisms, inking mechanisms, and gearing.

Fig. 2 is a longitudinal section on line 2—2, Fig. 1.

Fig. 3 is a side elevation partly broken away of such press.

Fig. 4 is a detail end view.

Figs. 5 and 6 are diagrammatical plan and sectional elevations of one arrangement of a two-deck press.

As shown the press is provided with two 110

- sets of perfecting mechanisms A and B; each of which sets preferably comprises two plate cylinders 1, 1^a, and two intermediate impression cylinders 2, 2^a, co-acting with 5 the plate cylinders, said cylinders being preferably arranged in one plane. Ink is supplied to the cylinders 1, 1^a, respectively from inking cylinders or drums 3, 3^a, to which ink is supplied from fountains 4, 4^a, 10 by means of suitable intermediate ductor and distributing rollers which are conventionally illustrated in the drawings. Each perfecting mechanism may be constructed substantially as described in my Patent No. 15 979,919 and requires no detailed description herein.

- When the invention is adapted to the use of single-page-tubular plates, as described in my aforesaid patents, I prefer to mount 20 the outermost journals of the plate cylinders in annular bearings 1^c which are slightly smaller in diameter than the cylinders and are connected to the bearings of the adjacent impression cylinders by narrow necks 1^a, 25 substantially as described in my Patent No. 979,919, so that single-page-tubular-plates may be slipped endwise over such bearings on or off the cylinders as described in my said patent. 30 The outer ends of the plate cylinders, in both sets A and B, are journaled in such bearings as described; and the driving gears are attached to the inner ends of the cylinders; and the gearing for driving the cylinders 35 in set A is at the ends of the cylinders opposite to the gearing of the cylinders in set B.

- The plate, impression and inking cylinders in set A are provided with intermeshing gears 5 on their inner ends; and the cylinders in set B are provided with intermeshing gears 5^a on their inner ends, so that all such cylinders may be rotated at the same peripheral speed. The cylinders in 45 each set may be driven by means of trains of intermediate gears 5^b from gears 5^c on a shaft 5^d which may be located intermediate the two sets of perfecting mechanisms, as indicated in Figs. 1 and 3.

- 50 If it should be desired to use only one set of printing mechanism the other set may be put out of operation by slipping one of the intermediate gears out of place; or in any other well known manner.

- 55 Above the printing mechanism A may be arranged a guide roller 6^a preferably extending the entire width of the press; and above the printing mechanism B may be arranged a guide roller 6^b preferably extending the entire width of the press.

- At the end of the press adjacent mechanism B and preferably below said mechanism may be arranged two sets of angle bars 7 and 7^a. At the same end of the press 65 may be also arranged one or more folders

F, F', to which the printed webs may be directed; only the formers of such folders are indicated in the drawings; the folder F is shown as in line with the printing mechanism A; and the folder F' as in line 70 with the printing mechanism B.

Auxiliary web guide rollers 6, 6^c, 6^d, 6^e, 6^f, are mounted in the frame at the proper points to direct webs to these folders.

Each plate cylinder is preferably made 75 long enough to carry two plates; so that each section of the press, if using single-page-tubular-plates, will print four pages, when fully plated. If the cylinders are made longer, so as to carry either three or 80 more page-plates, each section could print as much as six or more pages, by collecting at the folder.

Either section of the press as shown is 85 adapted to print two-page-wide webs, and each web may be fed if desired from a separate roll; but when both sections are to print it is preferable to supply both sections from a single four-page-wide web roll. Assuming it is desired to print from both sections, the wide web w may be led from a roll w' suitably mounted at one end of the machine to and over a guide 6 thence to and over a guide 6^b, where it is divided 90 longitudinally by means of a slitter S, of 95 any suitable construction. One half w' of the slit web is then led back from guide 6^b to and over guide 6^a, and then down between the plate and impression cylinders in mechanism A; then down under guide 6^c and then, if desired, to and under guide 6^e and over guide 6^f to the folder F, where it may be folded separately from the other half w² of the web which is printed in mechanism B.

The half w² of the web may be led from roller 6^b down between the plate and impression cylinders in mechanism B, then down under a guide 6^d, and then if desired be led to and over roller 6^f to the folder F' 110 and be folded separately from part w' of the web. If however it is desired to associate the webs at folder F the web w² after passing roller 6^d may be led over the angle bars 7 and brought into alignment with web w' and assembled therewith at the roller 6^f and passed therewith to the folder F. If desired web w' after passing roller 6^d may be turned over angle bars 7^a and brought into alignment with the webs w² and then 115 passed under rollers 6^e and assembled therewith at roller 6^f and led to the folder F'.

It should be noted that, by reason of the peculiar laterally displaced or staggered arrangement of the two printing mechanisms 125 lengthwise of the run of the web, both halves of the split double width web can be printed without any lateral deflection thereof prior to printing; just as if all the plates were mounted upon four page wide cylin- 130

ders. It will be observed that the construction combines the advantages of the single-page-tubular plate press, with the handling of the minimum quantity of paper rolls, and 5 retains the desired stiffness of construction, and convenience of operation, and accessibility of parts. For larger presses additional sets of printing mechanisms could be added by superposing them over the other 10 sets. For instance, a three-deck machine could have two duplicate sets of printing mechanisms placed over the single deck shown; and be driven through intermediate gears from the shaft 5^a. A three deck press 15 of this style would have a maximum capacity of 24 pages (using single-page-tubular plates) and would be fed from three rolls of paper; and such press would have a minimum capacity of two pages using one printing 20 section and one-quarter-width roll. In the same machine 4, 6, 8, 10, 12, 14, 16, 18, 20 and 22 pages could be run by disconnecting printing sections not required, and using full-width, or half-width, or quarter-width, 25 rolls as required.

In the example shown in Fig. 1, mechanism A is adjacent the right hand side of the press and mechanism B adjacent the left hand side of the press, looking from the web 30 roll end thereof; and in building presses with two or more decks, each an exact duplicate of the other, as above suggested, all the mechanisms A would be adjacent the right hand side of the press, and all the 35 mechanisms B adjacent the left hand side thereof.

In Figs. 5 and 6 I have indicated a multiple deck press in which instead of having the printing mechanisms in the deck arranged 40 exactly alike, the printing mechanisms are reversed in location in the alternate decks; and the mechanisms A in superposed mechanisms are adjacent opposite sides of the press, and the mechanisms 45 B are similarly arranged. Thus in the example shown in Figs. 5 and 6 the printing mechanism A in the lower deck is adjacent the right hand side of the press viewed from the roll end; while the similar mechanism 50 A' in the superposed deck is adjacent the left hand side of the press; also the printing mechanism B in the lower deck is adjacent the left hand side of the press, while the similar mechanism B' in the superposed 55 deck is adjacent the right hand side of the press. Presses built up in this way have more clearance between the superposed printing mechanisms.

When the press has a plurality of printing 60 decks, the folders can be arranged so that the webs from the several printing mechanisms may be led to the same folder, or to different folders as desired; and suitable deflecting or angle bars may be provided 65 so that the webs can be deflected, as-

sembled and directed to any desired folder. When superposed decks are used it will be possible to print and perfect webs in colors by leading them successively through different printing mechanisms.

While I have described the invention as embodied in a rotary press, and preferably in a single-page tubular-plate machine, the invention could be employed with other kinds of printing mechanisms.

While I have shown and described the folders as arranged at one end of the press, the folders could be arranged at the sides of the press if desired, and I do not consider the invention restricted to any particular arrangement or number of folding mechanisms.

What I claim is:

1. In a printing press, the combination of a pair of rotary printing mechanisms so arranged that the inner side of one mechanism overlaps the inner side of the other, whereby two narrow webs may be printed, or a full width web may be printed by dividing such web and leading one half thereof through each mechanism; with means for folding the printed halves of the web separately or together.

2. In a printing press, the combination of a main frame, two sets of separated rotary perfecting printing mechanisms therein arranged transversely of the main frame, the inner ends of the cylinders in one set overlapping the inner ends of the cylinders in the other set, and driving gearing at the inner side of each perfecting mechanism.

3. In a printing press, the combination of two sets of rotary perfecting printing mechanisms arranged transversely of the main frame, the inner ends of the cylinders in one set extending slightly past the inner ends of the cylinders in the other; means for operating the mechanisms, and means for folding their products separately or together.

4. In a printing press, the combination of a main frame, a plurality of separated printing mechanisms therein relatively displaced laterally of the frame, the inner end of each mechanism overlapping the inner side of the adjacent mechanism; means for directing a single or double width web through said press, and means for splitting a double width web before it reaches said mechanisms so that the halves of such web may be directed to separate mechanisms.

5. In a printing press, the combination of a plurality of superposed printing decks, each deck comprising a plurality of separated printing mechanisms so arranged that the inner side of one set overlaps the inner side of the adjacent set in the deck.

6. In a printing press, the combination of a main frame, a plurality of sets of printing mechanisms therein arranged transversely

- thereof, the inner side of one mechanism overlapping the inner side of the adjacent mechanism, and gearing on the inner end of the cylinders in the mechanisms; means for 5 directing a single or double width web through said press, and means for splitting a web before it reaches said mechanisms so that the halves of such web may be directed to separate printing mechanisms.
- 10 7. In a printing press, the combination of a main frame, a plurality of sets of printing mechanisms therein arranged transversely thereof, the inner side of one mechanism overlapping the inner side of the adjacent mechanism, means for guiding webs through said mechanisms, means for splitting a web before it reaches said mechanisms so that the halves of such web may be directed to 15 separate mechanisms; a plurality of folders, and means for directing the webs to either folder, whereby the printed webs may be delivered separately or together.
8. In a printing press the combination of two separated relatively laterally displaced 20 printing mechanisms, means for longitudinally dividing a wide web and means for directing the parts thereof respectively through the related printing mechanism without lateral deflection thereof.
- 30 9. In a printing press the combination of two adjacent separated printing mechanisms so arranged that the inner end of one mechanism overlaps the inner end of the other mechanism.
- 35 10. In a printing press the combination of adjacent separated printing mechanisms having their cylinders in axial parallelism, and arranged so that the inner ends of the cylinders in one mechanism overlap the inner 40 ends of the cylinders in the adjacent mechanism, substantially as described.
11. In a printing press the combination of two similar separate printing mechanisms arranged adjacent but one in advance of the other and in different vertical planes, means for longitudinally dividing a wide web and means for directing the parts thereof directly through the related printing mechanism without lateral deflection of either 50 part of the web.
12. In a printing press the combination of adjacent sets of printing mechanisms having cylinders in axial parallelism, and arranged in one main frame the inner ends of the cylinders in one set overlapping the inner ends of the cylinders in the adjacent set, substantially as described.
13. In a printing press the combination of two adjacent sets of printing mechanism 60 mounted in one frame and in substantially the same horizontal plane, and so arranged that the inner end of the printing couple in one mechanism overlaps the inner end of the printing couple in the other mechanism.
- 65 14. In a printing press the combination of two adjacent separated printing mechanism so arranged that the inner end of the printing couple in one mechanism overlaps the inner end of the printing couple in the other mechanism; means for longitudinally dividing a wide web and means for directing the parts thereof directly through the related printing mechanism without lateral deflection of either part of the web.
15. In a printing press the combination of a pair of separated relatively laterally displaced printing mechanisms arranged in the same frame; with means for folding the portions of web printed thereby.
16. In a printing press, the combination of two adjacent sets of printing mechanism so arranged that the inner end of the printing couple in one mechanism overlaps the inner end of the printing couple in the other; with means for folding the printed webs 85 separately or together.
17. In a printing press the combination of a pair of laterally displaced printing mechanisms arranged in the same frame; means for longitudinally dividing a wide web and 90 means for directing the parts thereof directly through the related printing mechanisms without lateral deflection; with means for folding the portions of printed web separately or together.
18. In a printing press, the combination of a pair of separated rotary printing mechanisms so arranged that the inner ends of the printing cylinders in one mechanism overlap the inner ends of the printing cylinders in the other mechanism, and whereby two narrow webs may be printed, or a full width web may be printed; with means for longitudinally dividing a wide web and means for directing the parts thereof directly through the related printing mechanism without lateral deflection of either 100 part of such web.
19. In a printing press, the combination of a plurality of superposed printing decks, 110 each deck comprising a plurality of sets of printing mechanism so arranged that the inner side of one set overlaps the inner side of the adjacent set in the deck, and means for directing a web or part of a web through 115 the printing mechanisms in each deck.
20. In a printing press, the combination of a plurality of superposed printing decks, each deck comprising a plurality of sets of rotary printing mechanism so arranged that the inner ends of the cylinders in one set overlap the inner ends of the cylinders in the adjacent set in the deck; with means for longitudinally dividing wide webs and means for directing the parts thereof directly through the related printing mechanisms in the decks without lateral deflection of the webs.
21. In a printing press the combination of a plurality of adjacent separated relatively 130

- staggered printing mechanisms arranged parallel within one main frame; with means for slitting a wide web and directing the halves of the web without lateral deflection 5 to the respective printing mechanisms.
22. In a printing press the combination of a plurality of rotary printing mechanisms arranged closely adjacent but in different vertical planes; with means for slitting a 10 wide web and directing the halves of the web without lateral deflection to the respective printing mechanisms.
23. In a printing press the combination of a plurality of separated printing mechanisms arranged in the same main frame and staggered in relation to each other; with means for slitting a wide web and directing the halves of the web without lateral deflection to the respective printing mechanisms. 15
24. In a printing press the combination of a plurality of separate printing mechanisms arranged adjacent and in the same frame and relatively staggered lengthwise of the run of the web whereby two narrow 20 webs may be printed or a wide web may be printed by dividing such web and leading the portions thereof through the respective mechanisms.
25. In a printing press the combination of a main frame and a plurality of separate similar printing mechanisms in said frame and relatively laterally displaced lengthwise of the run of the web whereby two narrow webs may be printed or a wide web may be 25 printed by dividing such web and leading the portions thereof through the respective mechanisms.
26. In a printing press, the combination of a main frame, and two separate printing mechanisms therein arranged one in advance of the other, and relatively laterally displaced lengthwise of the run of the web, whereby two narrow webs may be printed or a wide web may be 30 printed by dividing such web and leading the portions thereof through the respective mechanisms.
27. In a printing press the combination of a main frame, and a plurality of similar rotary printing mechanisms arranged there- 35 in adjacent but one in advance of the other and in different vertical planes, whereby two narrow webs may be printed or a wide web may be printed by dividing such web and leading the portions thereof through the respective mechanisms.
28. In a printing press, the combination of a plurality of superposed printing decks, each deck containing a plurality of separated printing mechanisms, the alternate sets of printing mechanism in each deck being arranged adjacent opposite sides of the press and relatively staggered lengthwise of the run of the web, whereby two narrow 40
- webs may be printed or a wide web may be printed by dividing such web and leading the portions thereof through the respective mechanisms.
29. In a printing press, the combination 70 of a plurality of printing decks, each deck containing a plurality of separated perfecting printing mechanisms, the alternate printing mechanisms in each deck being arranged adjacent opposite sides of the press 75 and relatively staggered lengthwise of the run of the web, whereby two narrow webs may be printed or a wide web may be printed by dividing such web and leading the portions thereof through the respective 80 mechanisms, and the printing mechanisms in the superposed decks also alternating in position with the mechanisms in the adjacent decks; with means for directing webs to the several mechanisms, and means for 85 folding the printed webs.
30. In a printing press the combination of a plurality of adjacent separated relatively staggered printing mechanisms arranged parallel within one main frame, 90 whereby two narrow webs may be printed or a wide web may be printed by dividing such web and leading the portions thereof through the respective mechanisms; with means for folding the printed webs or portions of webs separately or together. 95
31. In a printing press the combination of a plurality of similar separated and relatively laterally displaced printing mechanisms arranged parallel within one main 100 frame, whereby two narrow webs may be printed or a wide web may be printed by dividing such web and leading the portions thereof through the respective mechanisms; with means for folding the printed webs or 105 portions of webs separately or together.
32. In a printing press, the combination of two separated and relatively laterally displaced rotary printing mechanisms arranged in axial parallelism and one in advance of the other, whereby two narrow webs may be printed or a wide web may be printed by dividing such web and leading the portions thereof through the respective mechanisms; with means for folding the 110 printed webs or portions of webs separately or together.
33. In a printing press, the combination of two separately relatively laterally displaced rotary printing mechanisms arranged in axial parallelism one in advance of the other within a main frame and relatively staggered lengthwise of the run of the web, whereby two narrow webs may be printed or a wide web may be printed by 115 dividing such web and leading the portions thereof through the respective mechanisms.
34. In a printing press the combination of a plurality of separated printing mechanisms arranged adjacent and in substan- 120
- 125
- 130

- tially the same horizontal plane one in advance of the other and in different vertical planes in a main frame, whereby two narrow webs may be printed or a wide web
5 may be printed by dividing such web and leading the portions thereof through the respective mechanisms; with means for folding the printed webs or portions of webs separately or together.
- 10 35. In a printing press the combination of a pair of separated printing mechanisms arranged in the same frame and relatively laterally displaced lengthwise of the run of the web in substantially the same horizontal plane, whereby two narrow webs may be printed or a wide web may be printed by dividing such web and leading the portions thereof through the respective mechanisms; with means for folding the
15 portions of printed web.
- 20 36. In a printing press the combination

of a pair of separated relatively laterally displaced printing mechanisms arranged in the same frame; with means for directing webs or portions of the same web through such printing mechanisms without lateral deflection; and means for folding the portions of printed web. 25

37. In a printing press the combination of a plurality of printing mechanisms arranged in the same main frame and staggered in relation to each other lengthwise of the run of the web and adapted to operate upon split sections of the same web without deflection of the web sections. 30

In testimony that I claim the foregoing as my own, I affix my signature in presence of two witnesses.

HENRY F. BECHMAN.
